COIN CONVEYING MECHANISM

William G. Peters, Chicago, Ill., assignor to Richard Gretchen, Chicago, Ill.

Application January 13, 1936, Serial No. 58,912

12 Claims. (Cl. 194—98)

This invention relates to a coin handling mechanism and particularly to a means for moving, displaying and handling coins in a coin controlled or coin operated mechanism.

5 It has for one object to provide means for safeguarding the machine to prevent its unauthorized use. It has for another object to provide means for preventing the operation of the mechanism by a coin or token of the wrong size. Another 10 object is to provide such a controlling mechanism which is readily adaptable for use with coins of different sizes.

Other objects will appear from time to time in the specification and claims.

15 The invention is illustrated more or less diagrammatically in the accompanying drawings, wherein:—

Figure 1 is a general transverse vertical section of the mechanism of this invention;

20 Figure 2 is a section taken generally at line 2—2 of Figure 1;

Figure 3 is a section taken at line 3—3 of Figure 2;

25 Figure 4 is a detailed vertical section taken at line 4—4 of Figure 3, showing a coin or token in position;

Figure 5 is a plan view of the main coin carrying mechanism;

30 Fig. 6 is a side elevation of the coin carrier gate;

Figure 7 is a vertical section taken at line 7—7 of Figure 6;

Figure 8 is a perspective view of a portion of the gate shown in Figures 6 and 7;

35 Figure 9 is a horizontal section taken at line 9—9 of Figure 3, without coins;

Figure 10 is a horizontal section taken at line 10—10 of Figure 3, showing a coin in place;

40 Figure 11 is a plan view of the base plate of the coin handling means.

Like parts are designated by like characters throughout the specification and drawings.

The apparatus of the present invention may be applied to any coin controlled or coin operated

45 mechanism. It is associated with the mechanism, with a housing and with a coin slot, and so arranged and so operated that coins deposited in the slot, if they are the right size, fall into the conveying mechanism, are carried around and

50 subsequently dropped into the coin box or other receiving member.

As shown herewith the mechanism with which the coin conveyor is associated is omitted and is indicated only very slightly diagrammatically.

55 1 is a top or cover of a coin controlled or op-

erated mechanism, which it cut away to provide an opening 2. Secured to the top or cover 1 by a flange 3 and screws 4 is an irregularly shaped housing 5 which encloses the coin conveying mechanism and also closes the opening 2 so that 5 the housing 5, together with the housing of the machine to which the coin conveying mechanism is attached, forms in effect a complete housing for the complete machine. The housing 5 may be cut away as at 6 and this cut away portion 10 is closed by a transparent window 7 formed of glass, or other suitable material. The upper portion of the housing 5 is narrowed and reduced as at 8, is perforated as at 9 and is provided with an opening 10 through which a coin may be inserted. This opening receives a coin gauging member 11 which is removably held in place by a set screw 12 or otherwise. The purpose of the coin gauging member is to prevent the insertion of coins which are too large for the mechanism. 15 A coin gauging member suitable to the size of coins or tokens which are to be inserted into the machine is put in place and it may be removed and another substituted for it if the machine is subsequently to be operated with coins 20 or tokens of a different size.

A fixed coin chute which may be of any suitable design is positioned within the composite housing formed of the members 1 and 5, extends upwardly toward the reduced portion 8 and is 30 arranged to receive coins. As shown in the several figures, the coin chute comprises an upper, open portion 13, flared as at 14 and being laterally bent as shown particularly in Figures 2 and 4. The main body 15 of the coin chute continues 35 downwardly in an irregular path and terminates at any desired point to which coins are to be conducted. Along one side, as at 16, the coin chute is open to permit movement of coins into the conveying assembly. 17 is a portion of the 40 frame or housing of the main mechanism upon which the coin conveying assembly is mounted. It may be made, as shown particularly in Figure 3, to include or form within itself a part of the coin chute 15, although this is not an essential 45 feature of the invention. Resting upon the member 17 is a foundation plate 18 formed in its upper surface with a perforated, interiorly threaded boss 19. Resting upon this boss is a base plate 20 provided with a perforated, downwardly extending boss 21, which rests directly upon the boss 19. The base plate 20 is shown in plan in Figure 11. It is provided with a hollow section 22 which forms a portion of the coin chute 15. It is provided also with a relatively 50

narrower, downwardly extending coin slot portion 23 through which the coin passes after having passed about the conveyor assembly. Projecting downwardly from the under surface of the member 20 is a pair of perforated ears 24 which receive a pin 25 upon which a dog 26 is mounted for rotation. The free end of the dog is urged downwardly by a spring 27 which bears against the dog and the under surface of the member 20. The other end of the dog is provided with an upward projection 28 which may pass through a perforation 29 in the member 20. The member 20 is also provided with a generally arcuate slot or opening 30 the purpose of which will be described below. The member 20 is also perforated as at 31 to receive one end of a hinge pin 32 of a gate 33. A spring 34 is wrapped about the hinge pin 32 and bears at one end upon the gate 33 and at the other end upon a retaining pin 35 positioned in a perforation 36 in the member 20. The gate as shown particularly in Figures 3, 6 and 7 is provided with a generally straight side 36a and is sloped along its upper and lower edges as at 37 and 38, respectively. Extending into its straight face 36a the gate 33 is provided with a pair of slots 39. A gauge plate 40 is removably secured to the gate on its outer face by screws 41 or otherwise. This plate is provided with an inwardly projecting flange 42 which extends through the gate and beyond its inner or straight face 36a, as shown particularly in detail in Figure 7. The gate and plate are also perforated as at 43. That portion of the gate which lies between the slots 39 is provided with an inclined upper surface 44 as shown in Figure 3.

Screwed into the boss 19, extending upwardly from it through the perforated boss 21 is a holding screw or bolt 45. A hub 46 is positioned about the screw 45 and rests at one end upon the upper surface of the member 20. The screw 45 is enlarged as at 47 and the shoulder 48 rests upon the upper surface of the member 20. The screw 45 is again reduced above the enlarged portion 47 to receive an upper plate 49. A nut 50, screwed on the upper end of the screw 45, holds the plate 49 in position against movement. Secured to the hub 46 is an outwardly extending plate 51 having upwardly turned flanges 52. As shown particularly in Figures 5 and 10 the plate is octagonal in form and each of the flanges 52 defines one octagonal side. Obviously the plate might have more or less sides. 53 is a reinforcing or stiffening plate secured to the bottom of the plate 51 by rivets 54 or otherwise. If the plate 51 is of sufficient stiffness the reinforcing plate 53 might be omitted. Perforations 54a are formed through the plates 51 and 53 and there are as many perforations as there are sides to the conveyor. In the present case, therefore, eight perforations are provided.

Positioned about the exterior of the flanges 52 are two or more coin retaining rings 55 which on their exterior are curved or circular and on their interior are provided with straight portions 56, one for each of the sides 52, and there is thus defined on each side of the coin conveyor a space 57 which is bounded on one side by an upturned flange 52 and on the other side by the rings 55. As shown in the drawings, particularly in Figures 1 and 3, the coins 58, when they lie within the pockets 57, are supported upon the plate 20. The conveying assembly thus does not support the coin but serves to move it about in a manner which will be described below.

The plate 49, in addition to covering the coin conveying assembly, furnishes an upper bearing point for the hinge pin 32 of the gate 33.

Projecting downwardly from the under surface of the base plate 20 are two guide members 59, 60. These serve to guide and to position the pawl by means of which the coin assembly is moved. 60 is a pawl, pivoted at one end to an arm or lever 61. Projecting downwardly from the bottom of the pawl 60 is a hook member 62 to which one end of a spring 63 is secured. The other end of the spring is secured to any rigid support, for example, to a portion of the member 18 as at 64. The effect of the spring is to hold the pawl and arm in the full line position of Figure 1 when free to do so. At its outer end the pawl is provided with an engaging hook portion 65 which has an upper inclined or cam face 66. The arm 61 moves from the full line position of Figure 1 to the dotted line position of that figure in response to movement of some part of the machine with which the present device is associated. Each time this movement occurs the coin conveyor is rotated and this movement occurs step by step. Thus with the parts in the position shown in Figure 1 in full lines, the point 65 is penetrating through one of the perforations 54a. If the arm 61 is moved to the dotted line position, the coin conveyor is rotated an equal distance. In each stopping position the member 28 penetrates through one of the perforations 54a, but when the movement of the arm 61 just described occurs, the member 28 is forced downwardly, the spring 27 being compressed to permit this, and as soon as the conveyor has moved through one step, the member 28 is forced into the next perforation and again positions and holds the conveyor. When the arm 61 is free to return under the influence of the spring 63, the inclined or cam face 66 depresses the outer end of the pawl, bearing against the under surface of the conveyor, and so the nose or point 65 is withdrawn from the perforation and at the completion of the rearward movement to the full line position, falls into the next perforation 54a and the parts are in position for a further advancing step.

Several different safeguarding devices may be applied to the mechanism of this invention. As shown there are three positive means for preventing unauthorized, dishonest or incorrect use of the mechanism.

As shown particularly in Figure 3, a means is provided to prevent incorrect use by inserting a second coin or token before a previously inserted coin or token has been moved into the conveyor. This comprises an irregularly shaped member 67 which has an upper surface portion 68, downwardly inclined, and a lower surface portion 69, also downwardly inclined. Two ears 70 formed preferably on the downwardly inclined portion 69 are pivoted by means of a pin 71 supported in a base member 72 which forms a part of or is attached to the coin chute. When free to do so, the member 67 falls into and remains in the full line position of Figure 3. This movement is assisted by a counterweight 73. It will be noted that in this position the lower inclined portion 69 lies across or extends into the coin slot path 16. If now a coin is dropped into the machine it strikes this part of the portion 69 and depresses it, moving the member into the dotted line position of Figure 3. One edge of the member 69 is beveled or cut away as at 74, as shown particularly in Figures 4 and 9. It will be noticed also that each of the flanges 52 is provided with

5 a cut away portion 75 through which the lower end of the member 69 projects when the parts are in the position shown in full lines in Figure 3. The upper edge of each cut away portion 75 serves as a stop to limit the upward tilting movement 10 of the member 69. The coin slot is perforated or cut away as at 76 to permit the upper member 68 to penetrate through it. Thus when a coin has tilted the member 67 to the dotted line position of Figure 3, the upper inclined member 68 projects through the opening 76 into the coin slot and lies within the path of a coin falling from above so that should a second coin be deposited while the first still remains in contact 15 with the portion 69, the second coin, in falling, will strike the upper surface of the member 68 and will be deflected over the gate 33 to pass downwardly through the coin chute 15 to be discharged from the machine or otherwise disposed 20 of.

25 A second protective means comprises a part effective to prevent withdrawal of a coin or token once it has been deposited in the machine and fallen into the space 16 between the gate 33 and the conveyor. This comprises a member 77 pivoted at 78 and provided preferably with a laterally bent forked portion 79. A spring 80 tends to hold the member 77 in the position shown in Figure 9. A stop 81 limits movement of the member 30 in response to the spring. As shown in Figure 9, this member, therefore, is normally in inoperative position. It is ordinarily moved to operative position to prevent withdrawal of a coin when a coin has been introduced and the operation of the 35 total mechanism has been initiated. When this occurs a lever 82 which is pivoted at any suitable place, for example, at 83, and is secured to some part of the total mechanism so as to be moved by movement of the latter, swings outwardly from the position of Figure 1 and by means of a link 30 holds the member 77 against the resistance of the spring 80 so that the forked end 79 extends into the coin slot. Since it lies above the coin it prevents its withdrawal. For convenience the 40 member 79 is so positioned that in the movement just described it extends through a perforation or cut away portion 85 formed in the member 67.

45 A further means for preventing unauthorized or incorrect use of the machine comprises a member connected with some operating part, preferably an operating handle, of the main mechanism and is so arranged that it either prevents operation of that handle and hence prevents operation of the main mechanism, or else if it permits operation of the handle, makes it ineffective to operate the mechanism. This mechanism comprises among other parts a lever 86, which may be pivoted at 83 and which carries at its upper end a plunger 87 which extends through a suitable 50 perforation in the outer wall of the coin chute 15 and through a perforation 43 in the plate 40 and gate 33. When the handle or other operating means is operating, the total mechanism is actuated, the lever 86 is moved counter-clockwise, by a connection 88 which is suitably connected 55 to the main mechanism. Thus the plunger 87 is moved into the coin slot space 16. If no coin is present the plunger contacts nothing and moves across the slot through one of the perforations 89 60 in a flange 52, there being one perforation in each flange. This movement of the plunger across the space 16 and through the perforation actuates a control mechanism, not shown, either to prevent movement of the handle or to make it ineffective. Should there be a coin present in the 65

space 16 at the time that the plunger is moved as described, it will contact that coin and its movement is limited by the coin. This limited movement is effective upon the control mechanism not shown, and the operation of the total mechanism 70 is permitted.

75 It is to be understood that the operation and connection of the members 61, 82 and 86 with the main mechanism is not limited to any particular construction or details. These details form 10 no essential part of the present invention. It is sufficient that these parts are connected to the main mechanism to carry out the functions assigned to them and indicated in the above description.

15 The use and operation of my invention are as follows:

20 As has been pointed out above, the device of the present invention is really an accessory for use in connection with another mechanism which is 20 referred to as the main mechanism. This may be any sort of a coin controlled or coin operated mechanism. It may be a game device, a vending mechanism or anything else, and the controls of the coin handling or conveying mechanism of the 25 present invention are associated with, and to some extent operated by, the operating means of the main mechanism.

30 The device of the present application can be used with slight alterations for several different sizes of coins or tokens. It is assumed that a suitable gauge 11 has been inserted in the opening 19 of the coin slot and that a suitable gauge plate 40 carrying a suitable gauge extension 42 has been positioned in the gate. A coin or token of the proper size is now inserted and falls into the flaring opening 14 of the slot 13, passes downwardly into the space 16 between the gate 33 and one flange 52 of the conveyor. The coin strikes the member 69 and swings it to the dotted line 40 position of Figure 3, thus also swinging the upper portion 68 into the dotted line position covering the space 16. With the parts in this position, should another coin be inserted, it will strike on the top of the member 68, be deflected to the 45 right of the gate 33 and fall through the chute 16, either to be returned to the user or deposited in some other place, depending upon the final direction of the chute 15.

50 With a coin of the proper size now in position in the space 16 it occupies the position shown in elevation in Figure 4. It lies with its edge against one edge of the gauge plate 42 in a generally vertical position. Its edge is also caught by one of the rings 55 so that although there is 55 nothing directly below it it cannot fall further. With the coin in this position the operating handle or device of the main mechanism is operated. When this occurs the arm 61 is moved from the full line position of Figure 1 to the dotted line 60 position of that figure and the hook 67 passing through one of the perforations 54a pulls the conveyor around one step. To permit this movement the gate 33 yields outwardly against the spring 34. When the handle of the main mechanism is released the arm 61 is brought back by the spring 63, the hook being withdrawn from the particular perforation 54a in which it has been, by the camming effect of its inclined face 66 65 against the bottom of the conveyor. It stops in position beneath the next perforation 54a and snaps or projects upwardly through it to be in position for the next advancing movement of the conveyor. The inclined or beveled edge 74 of the member 69 contacts the walls of one of the per- 70 75

forations 75 and is retained in the dotted line in tilted position of Figure 3 until the conveyor has moved far enough to bring the next opening 75 into position so that the member 69 can fall through it into the full line position of Figure 3.

To prevent unauthorized or improper use two other operations occur. The lever 86 is also connected with the handle for operating the main mechanism and before the movement of that handle becomes effective to operate the main mechanism the lever 86 is moved to the left from the position shown in Figures 1 and 3 and if a coin is lying properly within the space 16 the plunger 87 will contact it, will limit further movement of the lever 86 and will thus make effective the further movement of the main operating handle. If no coin is present, the plunger continues and finally extends through one of the perforations 89 and this movement positively prevents rotation of the conveyor and is effective also, through a connection with the lever 88, to render ineffective the operation of the main mechanism. Thus unless a coin of the right size is present at the time of operation the main mechanism cannot be operated.

To prevent withdrawal of coins the lever 82 is provided which is also operated in connection with the operating handle or other means of the main mechanism. It is moved in a clockwise direction and through the link 84 draws the locking member 77 into such position that its forked end 79 extends across the space 16 and prevents withdrawal of a coin.

If the machine is operated properly the coin having once passed from the space 16 rolls along the upper face of the base plate 20, being moved and guided by the conveyor and held in an upright position by the sides of the flanges 52 and the rings 55. The coin moves about the plate until it finally reaches the coin slot 23 and it falls into that and passes to any desired final receptacle. It will be understood therefore that in this mechanism a coin or token of the right size moves first to a position in which it is suspended by gauging members and where it acts to permit operation of the machine. It then is moved about by the conveyor and may be visible through the transparent wall 7. It thus makes a step by step movement about a curved path and is finally deposited into a receptacle of any desired sort.

I claim:

1. In combination in a coin handling assembly, an entering coin chute and a receiving coin chute, and means for moving a coin from the entering coin chute and for depositing it in the receiving coin chute, said means comprising a conveying assembly including a rotary conveying wheel provided with a plurality of angularly disposed sides, a fixed transparent housing separate from and surrounding said wheel, and a retaining member formed as a part of said wheel positioned outwardly with respect to and surrounding said sides and forming with them a number of open sided peripheral coin receiving pockets, said wheel being positioned with respect to said entering chute to receive a coin, movable means co-operable with said retaining member initially for supporting the coin in position within a pocket of said wheel, means for rotating said wheel to move the coin from such initial position to deposit it in said receiving chute, other means for supporting a coin in said pocket during its movement from said initial position to said receiving chute, said coin during movement

of the wheel, being visible from the exterior of the housing through the open sides of the pockets.

2. In combination in a coin handling assembly, an entering coin chute, and a receiving coin chute, the entering coin chute and the receiving coin chute being out of alignment, and means for moving a coin from the entering coin chute and for depositing it in the receiving coin chute, said means comprising a conveying assembly including a rotary conveying wheel provided with a plurality of open sided coin receiving pockets, a fixed transparent housing separate from and surrounding said wheel, said wheel being positioned with respect to said entering chute to receive a coin, means initially for supporting the coin in position within a coin receiving pocket, means for rotating said wheel to move the coin from such initial position to deposit it in said receiving chute, and additional means for supporting said coin in its movement from said initial position to said receiving chute.

3. In combination in a coin conveyor, a fixed coin supporting base plate and a movable coin conveyor having coin pockets and being positioned thereabove, and means for rotating said conveyor, parts on said conveyor for spacing and balancing coins while the latter rest upon said base plate, and a coin receiving chute associated with said base plate into which coins are deposited after having been moved about said base plate in a predetermined path, and a movably mounted coin positioning and gauging gate positioned adjacent said coin conveyor and initially holding the coin in one of said pockets, and serving in part to support the coin prior to its contact with said base plate.

4. In combination in a coin conveying assembly, a coin conveyor proper, comprising a wheel-like member having sides, against which a coin may lie, and retainers extending beyond said sides and shaped to form in co-operation therewith a series of coin receiving pockets or spaces, each of said sides provided with a main opening, and a relatively smaller additional opening, means for rotating the wheel member and control instrumentalities aligned respectively with said openings and adapted to penetrate the same in accordance with predetermined operations of the mechanism.

5. In combination in a coin conveying assembly, a coin conveyor proper, comprising a wheel-like member having sides against which a coin may lie, and retainers extending beyond said sides and shaped to form in co-operation therewith a series of open sided coin receiving pockets or spaces, each of said sides provided with a main opening, and a relatively smaller additional opening, means for rotating the wheel member, and movable control instrumentalities aligned with the respective openings in the sides of the coin pocket and movable in response to operation of the wheel to penetrate said openings, at least one of said control members operating through the open sides of the pockets formed by said retainers.

6. In combination in a coin conveying assembly, a coin conveyor proper, comprising a wheel-like member having sides against which a coin may lie, and ring-like retainers extending around said sides and shaped to form in co-operation therewith a series of open sided coin receiving pockets or spaces, each of said sides provided with a main opening, and a relatively smaller additional opening, a pawl operatively engaging the wheel and means for moving it back and forth to rotate said wheel in a step by step movement, control

instrumentalities operatively associated with the wheel in alignment with the openings in the sides of the wheel pockets, and means for operating the control members in a predetermined manner for moving the same into penetrating engagement with their respective openings to control the movement of the wheel.

5 7. In a coin mechanism, a coin conveying and gauging assembly comprising a coin carrying wheel, having a plurality of angularly disposed sides and a co-operating coin supporting and gauging gate, said gate movably positioned adjacent said wheel to lie generally parallel to an adjacent side of said wheel, coin retaining members on said wheel and a coin retaining gauge plate on said gate, the coin being supported initially partly on said coin retainers and partly on said gauge plate.

10 8. In a coin mechanism, a coin conveying and gauging assembly comprising a coin carrying wheel, having a plurality of angularly disposed sides and a co-operating coin supporting and gauging gate, said gate movably positioned adjacent said wheel to lie generally parallel to an adjacent side of said wheel, coin retaining members on said wheel and a coin retaining gauge plate on said gate, the coin being supported initially partly on said coin retainers and partly on said gauge plate, and a safety device for preventing the insertion of a second coin prior to movement of said first coin, said device comprising a movably mounted member extending into the path of the coin, said member carrying a switch portion and adapted upon contact with a coin to be moved to bring the switch portion above the first mentioned coin and into the path of a following coin, the first mentioned coin while in position on said gauge member retaining the switch member in position to divert a second coin 15 away from said wheel.

20 9. In combination a coin handling assembly including an entering coin chute, a wheel-like member provided with a peripheral series of open sided coin receiving pockets, means for successively positioning said pockets in alignment with said coin chute, and means for initially supporting a coin within a wheel pocket in alignment with the chute, said supporting means comprising a movable member having a portion penetrating the open side of said pocket and being positioned 25 to be contacted by said wheel-like member and to be moved out of said pocket by said wheel in

its rotation to align a succeeding pocket with the coin chute.

10 10. In combination in a coin handling assembly, a coin chute, a wheel-like member mounted for rotation and provided with means defining a plurality of coin receiving pockets, means for successively aligning said coin receiving pockets with said coin chute, means for initially supporting a coin in the pocket aligned with said chute comprising a member pivoted on an axis substantially parallel to the axis of rotation of the wheel and having a portion extending into the path of movement of the wheel in the direction of movement of said wheel, said last mentioned portion of said member penetrating into a coin receiving pocket aligned with the coin chute, and means for resiliently urging said member into penetrating engagement with said pocket whereby upon rotation of the wheel to align successive pockets with the coin chute, said member successively engages the respective pockets.

15 11. In a coin handling mechanism, a coin chute, a coin conveying mechanism including a wheel-like member having a plurality of peripheral coin receiving pockets, said pockets being open at top and bottom and on at least one side, a base member for supporting said wheel member and functioning to close the bottom openings of said pockets, said base member being apertured in alignment with said coin chute, means for moving the wheel member to successively align the respective pockets with the coin chute and opening in the base member, and a combined coin gauge and supporting member penetrating a pocket aligned with the coin chute for initially 20 gauging and supporting a coin deposited in said pocket.

25 12. In a coin handling mechanism a coin chute, a wheel-like member provided with a plurality of upstanding peripheral tongues, means cooperable with said tongues for defining coin receiving pockets, said tongue members each being provided with an aperture, means for successively aligning said pockets with the coin chute, a pivoted guard member having a portion adapted 30 to penetrate a pocket aligned with the coin chute through the opening in the wall thereof, said guard member including a portion movable into the coin chute in response to movement of a coin 35 into said pocket.

40 WILLIAM G. PETERS.
